UNITED STATES PATENT OFFICE.

JACOB R. SNYDER, OF JOPLIN, MISSOURI.

AUTOMATIC SPRINKLING DEVICE.

1,144,619.

Specification of Letters Patent. Patented June 29, 1915.

Application filed January 29, 1914. Serial No. 815,221.

To all whom it may concern:

Be it known that I, JACOB R. SNYDER, a citizen of the United States, residing at Joplin, in the county of Jasper and State of Missouri, have invented certain new and useful Improvements in Automatic Sprinkling Devices; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in sprinkling devices for streets, parks, lawns, etc., and the invention has for its object to provide in a sprinkling system, a sprinkling apparatus which is raised above the surface of the street, park, lawn or the like and is maintained in such elevated position during the sprinkling operation and automatically recedes into its normal inoperative position immediately the sprinkling operation ceases.

A further object is to provide for effectively guarding against the sprinkler or sprayer being obstructed or choked by the dirt from the street or road-way, which would accordingly render the sprinkler inoperative until the obstruction should be removed.

With this object in view the invention consists in the novel construction and arrangement of the nozzle or sprayer which is actuated by the water pressure in order to raise the same into proper operative position and which is so constructed and arranged as to automatically recede to a point in line with the plane or surface of the street, park, lawn, etc., in which the sprinkling device is employed.

The invention further consists in certain other novel details of construction and in combinations of parts, all of which will be first fully described and afterward specifically pointed out in the appended claim.

Referring to the accompanying drawing: Figure 1 is a vertical sectional view through a sprinkling device constructed in accordance with this invention. Fig. 2 is a transverse sectional view taken on line 2-2 of Fig. 1. Fig. 3 is a transverse sectional view taken on line 3-3 of Fig. 1.

Like numerals of reference indicate the same parts throughout the several figures in

which; 1 indicates a plate which is preferably square in plan threaded centrally at 2 to receive the threaded casing 3, the said casing 3 being provided with a shoulder 4 to 60 bottom against the under surface of the plate 1 in order to provide a rigid and durable construction. As will appear from Fig. 1 the casing 3 is provided with a long central cylindrical bore 5 and a lower enlarged bore or chamber 6, a shoulder 7 being provided at the junction of the two bores as will appear from an inspection of the accompanying drawing. The bottom end of the casing 3 is threaded to receive a reducing coupling 8 by means of which the device is connected to the water supply, while the upper face 9 of the casing 3 is provided with a central depression forming a chamber 10 to receive a sprinkling nozzle 11 70 in the manner which will be presently described.

Referring particularly to Fig. 1, 12 indicates the upper portion of the automatically operated nozzle which is provided centrally with a cylindrical bore 13 and on its upper end with a flange 14, said nozzle 12 being internally threaded at 15 to receive its lower member 16 which is externally threaded at 17. By means of this construction the length of the nozzle can be increased or diminished in order to adjust the extent of lifting of the spray nozzle 11 above the plane or surface of the plate 2.

18 indicates a lower piston like member 90 which as will appear from Fig. 2 is webbed at 19 to allow water entering the chamber 6 to pass through the same, the said piston like member 18 carrying a central stem 20 having at its upper end a sprayer-member 95 proper of disk formation 21, said stem 20 being adjustably secured to the piston like member 18 by means of a nut 22 at the bottom end thereof so as to regulate the extent of lift of the disk 21 above the flange 14 of 100 the nozzle 12, and as will appear from the accompanying drawing a passage 23 is provided around the stem 20 so as to freely permit the water to pass upwardly through the nozzle 12 when the device is in operation. 105 The lower piston like member 18 is beveled at 24 and adapted to engage the shoulder 7 of the nozzle casing 3 to provide a stop against excessive upward movement of the nozzle 12.

110 It will be observed that, by providing the member 20 with the disk sprayer-member

21 and the member 12 with the flange 14 and by causing said disk to rest flat down upon said flange, when the head or pressure of water is off, the sprinkler will be effectively guarded against becoming obstructed by dirt from the street. It is further observed that the water, when turned on, will have the effect to first separate the disk sprayer-member 21 from the member 14, thus putting the sprinkler or sprayer in operation, and that subsequently the nozzle 12, 16 receives an outwardly thrusting movement, thus elevating the same together with the sprayer-member 21 in its open position 15 as indicated in Fig. 1.

Having thus fully described the several parts of this invention its operation is as follows: The device being applied in a street, roadway, park, lawn or the like with the 20 plate 1 flush with the surface of the street, roadway, park, lawn or the like the disk sprayer-member 21 on the stem 20 lies flat against the flange 14 of the nozzle 12, said disk sprayer-member 21 and flange 14 lying 25 within the recess or chamber 10 in the upper face of the nozzle casing 3 in such manner that the upper surface of the disk sprayer-member 21, is flush with the outer surface of the surrounding plate 1. In this position 30 the device presents no obstacle or obstruction to the smooth or unbroken surface of a street, roadway, park, lawn or the like and as such is not an impediment to travel or traffic or unsightly in lawns, parks or the like. When it is desired to bring the sprinkling device into operation the water supply is opened to the lower chamber 6 of the 35 valve casing 3 and immediately the water passes up around the stem 20 raising the disk sprayer-member 21 a predetermined distance above the flange 14 of the nozzle 12. Upon the raising of the disk sprayer-member 21 into this position which is as shown in Fig. 1 further pressure of the water supply 40 causes the piston like member 18 to be raised into position shown in Fig. 1, thus lifting the flanged end of the nozzle 12 and the disk 21 into position shown in full lines in Fig. 1. The water passing upwardly through the 45 nozzle 12 is caused to impinge against the un- 50

der surface of the disk sprayer-member 21 and be forced out between the said disk and the flanged end 14 of the nozzle 12, thus causing the water to leave the device in a fine spray which by reason of the construction herein shown causes the water to be distributed over a large area of ground. As long as the pressure from the water supply is being exerted upon the pipes the sprinkling apparatus is maintained in the position shown in Fig. 1. As soon, however, as the water supply is cut off the disk 21 drops upon the flanged end 14 of the nozzle 12 and the latter drops into inoperative position so as to carry its upper end and the disk sprayer-member 21 down into the recess or chamber 10 in the face of the nozzle casing 3.

Having thus described the several parts of this invention what I claim as new and desire to secure by Letters Patent of the United States is:—

A sprinkler of the type described, including a casing having a bore extending therethrough, said bore being enlarged at its lower end, said casing being arranged for application to a water-supply under pressure, a nozzle having an upper-end flange, said nozzle being arranged within the bore of said casing, the lower end of said nozzle having an enlargement received by the bore-enlargement of said casing, and a sprayer comprising a sprayer-member proper of disk-formation and a stem depending centrally from said sprayer-member proper within the bore of said nozzle and having a lower-end controlling member also received by said bore-enlargement of the casing, said disk sprayer member being arranged to be initially separated from the flange of said nozzle under the water-pressure and to lie flat upon the latter when water-pressure is removed therefrom, said nozzle together with said sprayer, being arranged to be subsequently elevated by water-pressure.

In testimony whereof, I affix my signature, in presence of two witnesses.

JACOB R. SNYDER.
